UNITED STATES PATENT OFFICE

2,505,586

CUTTER FOR REMOVING WALLPAPER

Albert Singer, Los Angeles, Calif.

Application December 26, 1946, Serial No. 718,459

2 Claims. (Cl. 30—169)

1

This invention relates to a cutter for removing wall paper and the like.

An object of my invention is to provide a cutter which has a plurality of working edges which may be operated with a minimum of effort and skill and at a minimum of expense in removing wall paper and the like.

Another object of my invention is to provide a cutter having working edges which diverge rearwardly from a point in such a manner that the point facilitates the initial cutting of the wall paper so that a quick and effective start may readily be effected.

Another object of my invention is to provide a cutter in which the actual cutting is facilitated because of a single point of resistance. In other words, a cutter having working edges which diverge rearwardly from a point so that the adjacent working edges assist each other, rather than working independently as in flat bladed scrapers.

Another object of my invention is to provide a cutter in which the handle is a substantial distance from the plane of the working edges thus eliminating any danger of injuring the hand of the user.

Another object of my invention is to provide a cutter in which the cutting edges are on the under side of the cutter which tends to sharpen the cutting edges as the cutter is used.

Another object of my invention is to provide a cutter for removing wall paper which comprises a blade having cutting edges in which the blade slopes outwardly from the cutting edges so that the blade turns the removed wall paper back upon itself.

Another object of my invention is to provide a cutter which may be made of a single sheet of material.

My invention has many other objects, advantages, and features, some of which, with the foregoing, will be set forth at length in the following description where I shall outline one form of my invention, which I have selected for illustration in the drawings accompanying and forming a part of the present specification.

In the drawing:

Fig. 1 is a perspective view showing the cutter of my invention in use,

Fig. 2 is a plan view of the cutter of my invention,

Fig. 3 is an end view taken as indicated by the arrow in Fig. 2, and

Fig. 4 is a cross sectional view taken on the line 4—4 of Fig. 1.

2

Referring to the drawings, the cutter of my invention comprise a blade portion 10 having edges 11, 12, 13 and 14 and a handle 15. The under surfaces of the edges 11 and 12 are beveled and sharpened to provide cutting edges 16 and 17 which diverge rearwardly from the point 18. One advantage of having the cutting edges on the underside of the cutter is that the cutting edges are sharpened as the cutter is used.

The advantage of having the cutting edges diverge from a point is that the point facilitates the initial cutting of the wall paper so that a quick and effective start may readily be made.

The blade portion 10 slopes upwardly and rearwardly from the cutting edges 11 and 12 to form a central ridge 10a which extends from the point 18 to the handle 15. This is an important feature, since as shown in Figures 1 and 4 when force is applied to the handle to move the blade along the surface of the plaster or the like 19, to remove paper or the like 20, the removed paper 21 is turned back upon the paper 20. It will readily be seen that the only portions of the cutter that contact the paper or plaster are the cutting edges 16 and 17 and the point 18.

The sides 13 and 14 adjacent the handle 15 are curved and shaped as shown at 22 and 23 in order to provide a convenient gripping surface for the hand of the user. As shown in Figure 1, the handle 15 is a considerable distance from the plane of the cutting edges 16 and 17. The advantage of this construction is that when the handle is gripped by the user's hand there will be sufficient clearance between the user's fingers and the surface of the plaster 20 to prevent any danger of injury to the user's fingers.

The cutter may be formed of a flat sheet of suitable material. After the sheet has been cut to the desired proportions, the blade portion may be bent along the ridge 10a until the cutter assumes the shape shown in the drawings in which the cutting edges 11 and 12 and the point 18 all lie in a single plane.

It is apparent that, if desired, the cutting edges 16 and 17 may be formed of tungsten, carbide or other like material.

The most important advantage of my invention is that the cutter may be operated with less effort and skill and to greater advantage in removing wall paper than any other device.

Another advantage of my invention is that the cutting edges 16 and 17 will penetrate into the plaster 19 only to a small degree, irrespective of the force that is applied to the cutter.

55 From the foregoing description taken in con-

nection with the accompanying drawings, it will readily be seen that the foregoing objects are accomplished by my invention, and that the uses, advantages, and operation of my invention will be readily understood by those skilled in the art to which the invention appertains. While I have described the form of my invention which I now consider to be the best embodiment thereof, I desire to have it understood that the form shown is merely illustrative and that the invention is not to be limited to the details disclosed herein, but is to be accorded the full scope of the appended claims.

I claim as my invention:

1. A cutter for removing wall paper from walls comprising a blade and a handle, said blade having a point at its forward end and having cutting edges diverging rearwardly from said point with said point and the entire lengths of said cutting edges lying in a single plane, said blade comprising two portions, each sloping upwardly and rearwardly from said cutting edges to a central ridge which extends rearwardly from said point at an acute angle to said plane, and said handle extending rearwardly from the rearward end of said blade in alignment with said ridge.

2. A cutter for removing wall paper from walls comprising an integral blade and handle, said

blade having a point at its forward end and having cutting edges diverging rearwardly from said point with said point and the entire lengths of said cutting edges lying in a single plane, said blade comprising two portions, each sloping upwardly and rearwardly from said cutting edges to a central ridge which extends rearwardly from said point at an acute angle to said plane, and said blade portions converging upwardly and rearwardly from the rearward ends of said cutting edges to merge with said handle which extends rearwardly from said blade in alignment with said ridge.

ALBERT SINGER.
